DESIGN FOR A DRESS

Elsye Kay, New York, N. Y.

Application March 26, 1940, Serial No. 91,237

Term of patent 3½ years

To all whom it may concern:

Be it known that I, Elsy Kay, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

I claim:

The ornamental design for a dress, substantially as shown.

ELSYE KAY.
